UNITED STATES PATENT OFFICE.

GEORGE S. GATCHELL, OF ROSELLE PARK, NEW JERSEY, ASSIGNOR TO THE SINGER MANUFACTURING COMPANY, OF ELIZABETH, NEW JERSEY, A CORPORATION OF NEW JERSEY.

THREAD-CONTROLLING MECHANISM FOR SEWING MACHINES.

Application filed March 10, 1921. Serial No. 451,188.

To all whom it may concern:

Be it known that I, GEORGE S. GATCHELL, a citizen of the United States, residing at Roselle Park, in the county of Union and State of New Jersey, have invented certain new and useful Improvements in Thread-Controlling Mechanisms for Sewing Machines, of which the following is a specification, reference being had therein to the accompanying drawings.

This improvement relates to thread-controlling mechanism for sewing machines, more particularly of the chain-stitch type and has for an object to provide a compact thread controlling mechanism of simplified construction which in a chain-stitch machine will accomplish the delivery and the taking up of the looper-thread, to and from the looper, in the proper amounts and at the proper times during the stitch-forming cycle to insure the uniform and correct formation of stitches with a minimum amount of the relatively expensive upper or needle-thread and a maximum amount of under or looper-thread of poor quality.

A further object of the invention is to provide a looper-thread controlling mechanism particularly adapted for installation in machines having the sewing point close to the standard or vertical member of the bracket-arm.

Still further, the invention has for an object to provide a looper-thread take-up which will permit the use of relatively weak looper-thread of poor quality and which will not tend to wind up the looper-thread, even though the latter should break while the machine is in operation.

In the embodiment of the invention illustrated the objects of the invention are attained by mounting upon the oscillating looper-carrier a thread-guiding fork between the tines of which oscillates a thread-cam mounted upon a vibratory looper-actuating lever. The cam is so shaped as to cooperate with the oscillatory thread-guiding fork to take thread from and pay it out to the looper as required for the correct formation of stitches. The looper-carrier also supports a pair of looper-thread nipper-springs which are depressed into contact relation with an adjustable stationary nipper-closing stop by the lateral motion of the looper-carrier in carrying the looper

from one side of the needle to the other at 55 the end of the loop-seizing stroke of the looper. The nipper-springs are thus held closed during the loop-shedding stroke of the looper. A suitable pull-off device is preferably provided for the looper-thread 60 at the supply side of the thread-nipper and its function is to provide slack thread to be drawn through the open nipper by the advancing looper, so that the looper may go forward on a loose thread and thus avoid 65 undue shortening of the previous looper loop lying on the under side of the work.

In the accompanying drawings, Fig. 1 is a side elevation of the bed of a sewing machine embodying the improvement, the 70 needle being at its highest point and the looper fully forward. Fig. 2 is a plan view of the same. Fig. 3 is a perspective view of the looper-carrier. Fig. 4 is a perspective view of the oscillating support for the 75 looper-carrier. Fig. 5 is a vertical sectional view through the bracket-arm standard transversely of the main-shaft. Fig. 6 is a view of the take-up elements at the period 80 of the cycle when the needle is fully down and the looper retracted. Fig. 7 is a similar view with the looper advancing to seize a needle-loop, and Fig. 8 shows the looper reTRACTING and the needle entering the triangle formed by the looper-thread 85 loop-blade and previous needle-loop.

In the specific embodiment of the invention illustrated, the sewing machine frame comprises a bed 1, bracket-arm standard 2 and head 3 in which the needle- and presser-bars are mounted; said bars carrying respectively, the needle 4 and presser-foot 5. The presser-foot 5 cooperates with a suitable four-motion feed-dog 6 which operates through the usual apertured throat-plate 7 90 let into the cloth-plate 8. It will be noted that, in the machine illustrated, the line of seam-formation represented by the position of the needle 4, is close to the standard 2, so that space between the sewing point and 100 the standard 2 for working parts beneath the cloth-plate 8 is at a premium.

Cooperating with the needle 4, below the throat-plate 7 is the looper 9 which is mounted on the looper-carrier 10 formed with an apertured and split hub 11 which is journaled for rocking movement upon the lateral pin 12 secured in the split socket 12'

forming a part of a rocking support 13 for the looper-carrier. The hub 11 is confined between the socket 12' and a collar 11' on the pin 12. The rocking support 13 is formed with a split hub which is tightly clamped upon the rock-shaft 14 suitably journaled in bearing supports on the bed 1 which latter constitutes a stationary support for the various moving parts. Fixed to 10 the inner end of the rock-shaft 14 within the standard 2 is a yoke 15 embracing a slide-block 16 on the eccentric 17 fixed to the main-shaft 18. This eccentric and the described connections therewith operate to 15 impart the usual sidewise or so-called "needle-avoiding" movements to the looper 9.

The looper derives its loop-seizing or end-wise movements through a train of connections including the link 19 joining the ball 20 on the looper-carrier with a similar ball at the upper end of the arm 21 of a bellcrank lever fulcrumed at 22 to the bed 1. The other arm 23 of the bellcrank-lever is connected by the pitman 24 to one arm 25 of an upper bellcrank-lever fixed to and having for its fulcrum support the usual needle-actuating shaft 26. The other arm 27 of the upper bellcrank-lever is connected by the pitman 28 to the crank 29 on the 30 main-shaft 18.

To avoid the danger of winding up the looper-thread, the present looper-thread take-up is made oscillatory in character, rather than rotary. Also it is of a character 35 such that it may be compactly installed in a short arm and bed sewing machine, where there would not be room for a rotary or other known looper-thread take-up. Mounted upon the looper-carrier is one 40 element 30 of a take-up comprising coacting thread-engaging devices, preferably of the coacting thread-guide and thread-cam type. In the embodiment of the invention illustrated the member 30 is the 45 thread-guide member and is in the form of a fork, the tines of which are apertured at 31 to receive the looper-thread *t*. The thread fork 30 is fixed relatively to the looper 9 and moves with the latter both end-wise and sidewise.

Cooperating with the oscillating thread-guiding fork 30 is the oscillating thread-cam 32 having the active edge 33 which passes between the tines of the fork 30. 55 The cam 32 is mounted on an arm 34, which is adjustably secured by means of a slot-and-screw connection 35 to a recessed seat 35', Fig. 5, in the arm 21 of the bellcrank-lever 21, 23.

60 The support 13 for the looper-carrier 10 is formed with a hub extension 36 on which is mounted the pair of thread-nipper springs 37 extending parallel to the rock-shaft 14. The opening and closing action 65 of the springs 37 is controlled by a stop-

screw 38 which is adjustably threaded into the bed 1.

A free supply of slack looper-thread may be assured if desired by providing a pull-off device comprising a pair of spaced arms 39 mounted on the pitman 28 and projecting forwardly through a slot 40 in the front side of the standard 2. Bisection the slot 40 is a cast-off plate 41. Mounted on the standard 2 at the sides of the path of motion 75 of the pull-off arms 39 are the thread-guides 42. As the crank 29 revolves, the free ends of the arms 39 are moved in an egg-shaped path, as shown in Fig. 5, and seize the looper-thread between the guides 42, lifting 80 said thread until the latter is cast off of the ends of said arms by the outwardly and upwardly inclined edge 43 of the cast-off plate 41. The pull-off action is timed to occur when the nipper-springs 37 are closed, 85 thereby providing a bight of slack thread which is drawn through the nipper-springs by the looper or take-up, when said springs are open. The amount of thread pulled off may be varied by adjusting the thread-guides 42 and the cast-off plate vertically; adjustable screw and slot connections 42' being provided for this purpose.

The operation of the take-up elements 30, 32 is substantially as follows:—Starting in 95 the position shown in Fig. 6 with the needle down and the looper retracted; as the looper advances to seize a needle-loop, the rising thread-eyes 31 and forwardly tilting edge 33 of the cam 32 operate to absorb thread 100 and take up the thread in front of the eye of the looper, thereby preventing buckling of the looper-thread. As soon as the looper beak is well into the needle-loop, or a little past the position shown in Fig. 7, the thread 105 between the guide-eyes 31 slips over the central hump of the cam-edge 33 and slack is afforded so that the looper may go forward to the end of its stroke, on a slack thread. When the looper reaches the end 110 of its loop-seizing stroke, Fig. 1, substantially all the slack looper-thread has been absorbed by the looper. As the looper moves sidewise in the early stage of its re-tracting stroke, the nipper springs 37 are 115 closed and the descending thread-eyes 31 coact with the cam-edge 33, to take up the thread given up by the retracting looper, as shown in Fig. 8. After the needle has entered the looper-loop, the thread between 120 the guide-eyes 31 slips downwardly over the central hump of the cam-edge 33 and slack looper-thread is afforded to permit the needle-loop to be readily and fully tightened so as to draw the requisite amount of slack 125 looper-thread into the stitch being formed. By the means described, correct formation of the stitches is assured without straining the looper-thread; the needle-loops being fully drawn up and only the tips thereof 130

being visible at the under side of the work. The use of a maximum amount of looper-thread and a minimum amount of needle-thread is thus assured.

5 The invention is not to be understood as limited to the precise construction and arrangement of parts shown and described as various modifications within the scope and spirit of the invention will doubtless be suggested to those skilled in the art from the foregoing disclosure.

Having thus set forth the nature of the invention, what I claim herein is—

1. Looper-thread controlling mechanism 15 for sewing machines comprising a thread-carrying looper having the usual endwise and sidewise movements, and a looper-thread take-up including coacting thread-engaging devices one of which is fixed relative to said

20 looper.

2. Looper-thread controlling mechanism for sewing machines comprising a thread-carrying looper having the usual endwise and sidewise movements, and a looper-thread 25 take-up including coacting thread-guide and thread-cam elements, one of which is fixed relative to said looper.

3. In a sewing machine, in combination, a reciprocating needle, a thread-carrying looper, a thread-guide moving with said looper and an oscillating cam cooperating with said 30 thread-guide to control the looper-thread.

4. In a sewing machine, in combination, a reciprocating needle, a thread-carrying looper, a looper-carrier, an oscillating lever and 35 connections for imparting loop-seizing and shedding movements to the looper-carrier, and cooperating thread-cam and thread-guide elements mounted on said looper-carrier and oscillating lever.

40 5. In a sewing machine, in combination, a reciprocating needle, a thread-carrying looper, coacting looper-thread guide and cam elements mounted to oscillate about independent fulcra, and means for oscillating said thread-guide and cam elements in time with the needle and looper.

45 6. In a sewing machine, in combination, a looper, a looper-carrier, a thread-guiding fork mounted on the looper-carrier and an oscillating thread-cam operating between the tines of the thread-fork to control the looper-thread.

7. Looper-thread controlling mechanism 50 for sewing machines comprising, a looper, means including a looper-carrier for imparting the usual loop - seizing and sidewise movements to the looper, and coacting

thread-guide and thread cam elements for the looper thread, one of said elements being 60 mounted on the looper-carrier.

8. Looper-thread controlling mechanism for sewing machines comprising, a looper, means including a looper-carrier for imparting the usual loop - seizing and sidewise 65 movements to the looper, a thread-guide mounted on the looper-carrier, and a thread cam cooperating with said guide to control the looper-thread.

9. Looper-thread controlling mechanism 70 for sewing machines comprising, a looper, means including a looper-carrier for imparting the usual loop - seizing and sidewise movements to the looper, a thread-guide mounted on the looper-carrier, and an os- 75 cillatory thread-cam cooperating with said guide to control the looper-thread.

10. Thread-controlling mechanism for sewing machines comprising coacting thread-guide and thread-cam elements mounted to 80 oscillate about spaced axes, and means for oscillating said elements synchronously.

11. Thread-controlling mechanism for sewing machines comprising coacting thread-guide and thread-cam elements mounted to 85 oscillate about spaced axes, and means for oscillating said elements synchronously and simultaneously in the same angular direction about their respective axes.

12. Thread-controlling mechanism for sewing machines having, in combination, a pair of pivoted arms, a link connection between said arms, means for oscillating said arms, a thread-guide mounted on one of said arms, and a thread-cam mounted on the other of 95 said arms in cooperative relation with said thread-guide.

13. In a sewing machine, in combination, a thread-carrying looper, a looper-carrier, a rocking support for the looper-carrier, a 100 thread-nipper mounted on said rocking support, and a looper-thread take-up including coacting thread-cam and thread-guide elements one of which is mounted on and derives its movement from the looper-carrier. 105

14. In a sewing machine, in combination, a looper, a looper-carrier, a rocking support for the looper-carrier, a pair of thread-nipper springs mounted on said support in substantial parallelism with the axis of rocking motion of the latter, and a stop coacting with said springs. 110

In testimony whereof, I have signed my name to this specification.

GEORGE S. GATCHELL.
